PORTABLE SUNDIAL

Joseph McAuliffe, Idaho Springs, Colo.

Application December 31, 1936, Serial No. 118,529

4 Claims. (Cl. 33—62)

This invention relates to a portable sun dial and has for its principal object the provision of a neat, compact, highly efficient unit which can be used to determine the hour of the day by the sun in any latitude, and which can be easily carried upon the person.

It is more particularly designed for use by campers, hunters, travelers, and explorers who might lose or damage ordinary time pieces and who have no access to a clock. It is also valuable for instructing classes in schools, boy scout troops, etc., in the fundamentals of time determination and astronomy.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:—

Fig. 1 is a face view of one form of the improved portable sun dial as it would appear in use.

Fig. 2 is a side view thereof.

Fig. 3 is a face view of an alternate form of the invention.

Fig. 4 is a longitudinal section through the form of Fig. 3, taken on the line 4—4, Fig. 3.

Fig. 5 is a detail view of the roll operating mechanism of the form of Fig. 3.

The invention comprises a board 10 of any suitable material such as cardboard, wood, bakelite fiber, etc. At the top of the board are two hinged flaps 11 and 12. The face of the flap 11 is provided with a narrow slot 13 and the face of the flap 12 is provided with a vertical indicating line 14. The flaps 11 and 12 are mounted upon suitable hinges 15 so that when not in use, they may lie flat against the board 10 and, when in use, they will stand upwardly at right angles to the surface of the board and parallel to each other. The slot 13 is aligned with the line 14 on a horizontal line 41 across the board.

A latitude plate 16 is pivoted upon a suitable pivot rivet extending through the board 10. Adjacent the rivet 17, the latitude plate passes through an arcuate slot 18, and is secured to the board on the rear face thereof. The plate 16 can be set at any desired angle by means of a clamp screw 19 which passes through an arcuate slot 20 and terminates in a clamping head 21 on the rear of the board.

Adjacent the slot 20 is an arcuate latitude index or dial 22 which is visible through a window 23 in the plate 16. An indicating arrow 24 indicates positions on the dial 22. The dial is indexed in all of the latitudes in which the invention is expected to be used. A scale running from 20° to 60° is usually all that is necessary.

A calendar is printed or engraved upon the plate 16, as shown at 25. The calendar is printed in two sections, with the months from July to November at one side, and the months January to May at the other side, and with the two remaining months June and December at the extremities as illustrated. The calendar is accurately laid out by projection from a declination scale 40 on the latitude plate 33. The declination scale is indexed to a mid-leap-year declination.

The two sections of the calendar are separated by means of a calendar slot 26. A flexible string 27 terminating in a plumbweight 28 extends through the slot 26 from a suitable head on the back thereof. The weight 28 is slideable along the string 27 and may carry an indicating pointer 42.

Below the plate 16 on the board 10 is a removable time chart 29 which may be clamped thereon by means of clamp nuts 30. Upon the time chart 29 are two hour circles 31 and 32, the circle 31 designating the A. M. hours, and the circle 32, the P. M. hours. The time indications of each hour circle are joined to those of the other by means of a series of vertical guide lines 43. The charts 29 must be changed to correspond with the latitude of the place where the dial is to be used. As illustrated, a "Lat. 40" chart is shown on the board 10.

In use, the user turns the flaps 11 and 12 to the vertical position as illustrated. He then sets his latitude plate 16 on the dial 22 to correspond with the chart 29 and with the place of use. As illustrated, the plate is set at 40° latitude. He now slides his string 27 along the slot 26 to bring it opposite the approximate day of the month. He now swings the string 27 over the 12 noon mark on the hour circles (which is directly over the pivot point of the plate 16) and slides the weight 28 along the string until the point of the indicating arrow 42 indicates the exact noon point. The board is now set for use.

By holding the board 10 in a plane intersecting the sun and inclining it to the proper angle, the sun's rays will shine through the slot 13 forming an image on the flap 12. By tilting the board to the right or left, this image is brought directly upon the line 14 of the flap 12. At this time the string 27, due to its weight 28, is hanging verti-

cally across the time chart 29 and the indicating arrow 42 on the weight will indicate a certain one of the vertical guide lines 43. If it is morning the time can be read by following this line upward to the A. M. hour circle 31, and if it is afternoon, the hour is read by following the line downward to the P. M. hour circle 32. As illustrated the dial is indicating either A. M. or P. M. depending, of course, on whether the dial is being used in the morning or the afternoon. By careful holding and accurate manufacturing, the time can be foretold accurately in five minute intervals.

Ordinarily, the device will be used in the same 15 latitude at all times so that the chart 29 need not be often changed. For travelers or explorers, however, who are constantly changing their latitude, the charts must be constantly changed to correspond thereto. An alternate form of the 20 invention to facilitate this constant change is shown in Figs. 3 and 4.

In the latter form a latitude plate 33, similar 25 to the plate 16, is pivoted on a side bracket clip 34, so that it extends over the 12 noon point on a time chart printed on the face of a relatively long paper strip 35. The strip 35 contains a series of time charts 36, each laid out for a particular latitude. The latitude for which each chart is to be used is indicated by an index such 30 as shown at 37. The strip 35 reels and unreels from a pair of rollers 38 operated from a thumb button 39, on the side of the device. The thumb button may operate the rollers directly, or it may be connected with both rollers through suitable 35 gears 44 and friction discs 45, as illustrated. This enables the user to quickly change his time charts to correspond to the latitude of the place of use. As each chart is brought into position its 12 noon point must be brought directly beneath the pivot point of the latitude plate. This 40 positioning is facilitated by printing an indication 46 on the strip at each time chart to be aligned with a corresponding indication 47 on the board.

While a specific form of the improvement has 45 been described and illustrated herein, it is desired to be understood that the same may be varied, within the scope of the appended claims, without departing from the spirit of the invention.

Having thus described the invention, what is 50 claimed and desired secured by Letters Patent is:—

1. A portable sun dial comprising: a flat board; a pair of upstanding members parallel to each other on said board, there being a slot in one of said members and an alignment indication on the other of said members to align said board

with a ray from the sun; a movable plate on said board; a flexible member depending from said plate; an hour scale intersected by said flexible member when said board is in alignment with said ray; a latitude scale upon said board; means for aligning and setting said plate at a desired indication on said latitude scale; a calendar scale on said plate; and means for varying the position of said flexible member with reference to said calendar scale. 10

2. A portable sun dial comprising: a flat board; a pair of upstanding members parallel to each other on said board, there being a slot in one of said members and an alignment indication on the other of said members to align said board 15 with a ray from the sun; a movable plate on said board; a flexible member depending from said plate; an hour scale intersected by said flexible member when said board is in alignment with said ray; a pair of rollers extending laterally of 20 said board; and a continuous strip of flexible material reeling from one roll to the other for carrying a series of differing hour circles.

3. A portable sun dial comprising: a flat board; a declination plate pivoted adjacent one side edge 25 of said board so as to swing over the face thereof; a latitude scale for determining the position of the said declination plate; means for locking said plate at any desired position on said latitude scale, said plate having a slot extending across 30 its face at right angles to a radius extending to its pivot; a plumb line depending from said slot downwardly over said board; a calendar scale along said slot for determining the point of suspension of said plumb line; an hour scale below 35 said declination plate over which said plumb line extends; and means for aligning said plate with a ray from the sun.

4. A portable sun dial comprising: a flat board; a declination plate pivoted adjacent one side edge 40 of said board so as to swing over the face thereof; a latitude scale for determining the position of the said declination plate; means for locking said plate at any desired position on said latitude scale, said plate having a slot extending across 45 its face at right angles to a radius extending to its pivot; a plumb line depending from said slot downwardly over said board; a calendar scale along said slot for determining the point of suspension of said plumb line; an hour scale below 50 said declination plate over which said plumb line extends; means for aligning said plate with a ray from the sun; and a head member on said plumb line preventing the latter from pulling from said slot, said head being clamped between said declination plate and said flat board. 55
